FIG. 1

FIG. 2

FIG. 3

FIG. 4

FIG. 5

FIG. 1 is a perspective view of an intravenous needle hub showing my new design; the broken lines illustrating the second hub indicate the interfitting relationship of the intravenous needle assembly;

FIG. 2 is a perspective view of the intravenous needle hub; the opposite side is a mirror image of the side that is shown;

FIG. 3 is a side elevational view of the needle hub of FIG. 2;

FIG. 4 is a plan view as seen from the right side of FIG. 2; and

FIG. 5 is a plan view as seen from the left side of FIG. 2.

The broken lines are shown for illustrative purposes only.

This is a continuation-in-part of Design application Ser. No. D. 1,623, filed Mar. 24, 1966 and now abandoned.

I claim:

The ornamental design for an intravenous needle hub, substantially as shown and described.
